(57) **CLAIM**

The ornamental design of a handle for folding upright vacuum cleaner, as shown and described.

DESCRIPTION

FIG. 1 is a perspective view of a handle for folding upright vacuum cleaner showing my new design;
FIG. 2 is a right side elevational view thereof;
FIG. 3 is a front elevational view thereof;
FIG. 4 is a left side elevational view thereof;
FIG. 5 is a rear elevational view thereof; and,
FIG. 6 is a top plan view thereof.
The details shown in broken lines are for illustrative purposes only and form no part of the claimed design.
